UNITED STATES PATENT OFFICE.

GUSTAV ULLMANN, OF VIENNA, AUSTRIA.

METHOD OF AND APPARATUS FOR CLEANING HIGH-PRESSURE BOILING APPARATUS.

Application filed August 23, 1926, Serial No. 131,090, and in Austria August 28, 1925.

In the high pressure boiling apparatus employed in industry for purifying or for dissolving different materials the pressure must be released i. e., a so-called blow-off must be effected prior to the treatment following on the boiling operation. The pressure has hitherto been released simply by opening a blow-off valve provided generally in the upper part of the boiler. This method of operation presents a number of disadvantages which are hereinafter explained as regards high pressure boiling apparatus employed in the textile industry for cleaning the raw material.

After the conclusion of the boiling operation which usually takes a few hours, the alkaline solution has absorbed the impurities contained in the textile materials. During the boiling operation the material is more or less packed together and a layer of scum or mud like matter consisting of this solution and impurities, collects above the material. If the blow-off valve be opened not only does the steam produced by the release of the pressure pass off but considerable quantities of the solution are carried off with it due to the continued evaporation. If the boiler is blown off into the atmosphere these impurities are spread into the immediate surroundings. The surrounding air is laden with evil smelling and unsanitary particles of alkali and such, and neighbouring vegetable growth is destroyed. The blowing off of the hot solution under pressure into the blow off gutter or the like which is also effected destroys the walls of the gutter in a short time. Moreover as a result of the long continued evaporation very often too much of the solution escapes and the material being cleaned is no longer completely covered by the liquid and air penetrates the fibres soaked with the solution as a result of which vegetable textile fibres as is well known are seriously damaged. Apart from this the dirtiest mud like portions of the solution immediately above the material remain in the dome of the boiler and in the subsequent washing generally effected by water flowing downwardly from the upper end through the boiler such portions are carried through the whole contents of the boiler again so that not only is the washing out of the boiler rendered difficult but the dirt which is difficult to remove subsequently settles on the already treated textile fibres.

The subject of the present invention is a method of an apparatus for blowing off and at the same time cleaning high pressure boiling apparatus by which the disadvantages set forth above are completely avoided. The essence of the invention resides in this that simultaneously with the opening of the blow off valve water or other cleaning liquid is introduced into the boiler as a result of which the scourings are diluted and the mass of scum and mud collected particularly in the dome portion washed away. By this method moreover the duration of the blowing off operation is considerably shortened.

The impurities taken up by the solution present the further disadvantage that in boiling apparatus having pre-heaters the impurities settle in the tubes of the pre-heater. Experience has shown that the impurities adhering to the tube walls of the pre-heater can easily be removed as long as no cooling has occurred. After the conclusion of the blow-off and after cooling of the pre-heater the impurities adhere so firmly that they can no longer be simply washed away and consequently the tubes of such pre-heaters have hitherto been gradually reduced in diameter by hard coatings which settle on them which coatings affect the transfer of heat and extend the time of treatment. Eventually the tubes have to be removed and freed from the adhering incrustation by a laborious process which generally seriously damages the tubes.

In accordance with the present invention this disadvantage is also avoided by washing the pre-heater directly after the conclusion of the boiling process i. e., at the same time as the pressure in the boiler is released, the solution flowing out of the boiler (which solution is being diluted by the cleaning liquid introduced into the boiler) being preferably led through the pre-heater and serving for washing the latter.

The invention includes apparatus for carrying out the new method and also all methods of using high pressure boiling apparatus in which the release of the pressure presents similar difficulties to those in apparatus for cleaning textile materials; for example in apparatus for treating cellulose and the like.

Two embodiments of high pressure boiling apparatus in accordance with the invention and suited for cleaning textile fibres are illustrated in the accompanying drawing.

Figure 1 shows the boiler alone with this improvement and Figure 2 shows the boiler with a preheater attached. The letters apply to equivalent parts in both figures.

5 Referring to the drawing *a* denotes the boiler which in the usual manner is provided with upper and lower perforated sieve plates *b* and *c* between which the material to be treated is introduced and it may be made 10 sectional to facilitate removal. To the cover *d* is connected the blow-off pipe *f* which is provided with a valve *g* and extends into a receiver *h*. In the domed space *i* is located a pipe *j* formed with perforations distributed 15 over its length and connected by means of a pipe *k'* and a three-way cock *w* with a water pressure supply. The pipe *j* is so arranged as not to interfere with the introduction and removal of the material to be treated. Water under pressure can also 20 be supplied by means of a pipe *k²* having a valve *x* to a pipe *o* into which leads the draw-off pipe *p* of the receiver *h*. The water under pressure flows through a nozzle 25 *q* into the pipe *o* and in consequence has an ejector action on the liquid flowing out of the receiver *h*. The pipe *o* like the draw off pipe *r* of the boiler *a* opens into the gutter *s*. By means of a separate pipe *k⁴* cold water 30 can be introduced into the container *h*.

On the conclusion of the boiling or like operation the blow-off valve *g* and the water valve *w* are opened, and the dirty upper part 35 of the solution, therefore, is forced by the water under pressure into the receiver *h* and is condensed by the cold water contained therein. A partial vacuum is thus produced in the receiver *h* which vacuum considerably accelerates the outflow of the liquid from 40 the boiler. This cold water, the pressure of which must always be somewhat greater than that within the boiler can be preheated or may contain admixtures. The water flowing into the dome *i* dilutes the solution 45 therein and washes the dome thoroughly while at the same time protecting the material under treatment from contact with air. The textile material between the perforated sieve plates *b*, *c*, remains full of solution as 50 the water flowing from the pipe *i* passes off through the pipe *f* which presents a smaller resistance to the water than the mass of textile material.

The release of the pressure and the blow-off of the boiler requires only quite a small 55 part of the time hitherto required for this purpose while by the dilution of the solution being discharged all the disadvantages referred to above are avoided.

60 After the blow-off the dome *i* of the boiler in which the greatest part of the impurities had collected, is thoroughly cleaned and in consequence subsequent washing of the material can be effected with much less work, 65 in a much shorter time and much more ef-

fectively than usual, because the impurities contained in the dome *i* are no longer spread over the whole mass of material and no longer require to be washed out of such material by protracted operations. At the same 70 time the textile material so long as it is covered with hot solution is effectively protected from contact with air and the solution remaining in the boiler is not substantially diluted and consequently it can be used 75 again.

In the embodiment illustrated in Fig. 2 is shown a high pressure boiling apparatus provided with the pre-heater *t* in which the solution is led in circulation through the 80 boiler *a* and through the tubes of the pre-heater *t* by means of a pump or the like and the pipes *f* and *r*. The water under pressure for washing the dome *i* passes into the boiler *a* through the pipe *k* which is adapted 85 to be closed by a valve *k'*. The receiver *h* is connected with the tube system arranged in the pre-heater *t* by a pipe *u* in which is interposed a valve *v*. As in the construction shown in Fig. 1 the outlet pipe *p* opens into 90 a branch *o* leading to the gutter in which branch is arranged a nozzle *q* to which water under pressure is supplied by means of the pipe *k²* fitted with a valve *x*. The branch *k* serves for filling the receiver *h* with water. 95

On blowing off the boiler the circulation pump for the solution is first stopped, then the valves *v*, *w* and *x* are opened so that the solution flowing off passes through the tube system of the pre-heater *t*, washes it and only 100 then passes into the receiver *h*. The liquid flowing through the pre-heater *t* which liquid is gradually becoming cleaner carries off with it the impurities produced in the previous boiling operation and clinging to the walls of the tubes and leads it away in one working operation with the blowing-off 105 operation.

In the pipe *f* is disposed a three-way cock *z* to which a third water pressure pipe *k³* 110 is connected. By means of this three-way cock, the boiler *a* can be filled with water independently of the pre-heater *t* while the pre-heater can be washed independently of the boiler *a*. 115

Between the dome *i* and the receiver *h* may be provided a separate pipe corresponding to the pipe *f* in the construction shown in Fig. 1, so that in blowing-off the boiler *a*, the pre-heater may be cut off if it is unnecessary to wash out the latter. 120

The invention is applicable to high-pressure boiling apparatus of all kinds, even those provided with a central circulating pipe or those in which the blow-off valve 125 is disposed at the lower end of the boiler. In such latter circumstances the cleaning liquid is introduced into the bottom space of the boiler. The cleaning liquid may, even in boilers fitted with a blow-off valve ar- 130

ranged in the cover, be led to the bottom space of the boiler. It must then pass upwardly through the material treated from beneath, so that the blow-off takes longer and the solution is diluted and cannot be used again. This method has, however, the advantage that the material is cleaned in blowing-off.

What I claim is:

- 10 1. A method of cleaning high pressure boiling apparatus employing chemical solution for purifying or dissolving materials, on release of the pressure within said apparatus, comprising, introducing into the boiler at the same time as it is blown off, a cool liquid diluent for diluting and cooling the solution and sludge thereof which are to be blown off from said boiler.
- 15 2. A method of cleaning high pressure boiling apparatus employing chemical solution for purifying or dissolving materials, said apparatus having a preheater in conjunction with the boiler comprising, introducing into the boiler at the same time as it is blown off, a cool liquid diluent for diluting and cooling the solution and the sludge thereof which are to be blown off from said boiler, and simultaneously washing out the preheater with the diluted solution issuing from the boiler.
- 20 3. The method as claimed in claim 1 comprising the additional step of leading through the preheater the hot solution which is being continuously diluted by liquid introduced preferably into the top part of said boiler and using such solution to wash out the preheater.
- 25 4. A method of cleaning out pressure boiling apparatus which includes besides the boiler, a preheater and a condenser, comprising introducing into the boiler adjacent the top at the time the boiler is blown off of a cool liquid diluent for diluting and cooling the solution and sludge thereof which are to be blown off from the boiler and at the same time washing out the preheater with

the hot solution which is being continually diluted by the cool liquid diluent, said diluted solution being led into said condenser, mixed therein with cooling water and thereby still further diluted and then led off into the open at a pressure approximately that of the atmosphere.

5. Apparatus for purifying and charging or dissolving material through the agency of a hot chemical solution comprising a boiler having a dome, a perforated sieve plate within said boiler, a distributing pipe extending into said boiler for introducing a diluting liquid to said boiler at the time of blowing off said boiler, said distributing pipe being located in the dome above the perforated sieve plate, and a condenser through which is discharged the solution diluted by the introduced liquid and freed from pressure above that of atmosphere.

6. Apparatus as claimed in claim 5 including a waste pipe connected to the condenser, an injector intercalated to said waste pipe and means for feeding water under pressure to said injector whereby the solution from said condenser is further diluted and drawn off.

7. Apparatus as claimed in claim 5 including a preheater interposed in the path of the solution discharging from said boiler.

8. Apparatus for the purifying and dissolving of material through the agency of a hot chemical solution including a boiler, a blow off conduit therefor, a pipe for supplying liquid under pressure to said boiler at the time of blowing off the boiler for diluting and cooling the liquid and sludge of the chemical solution, a preheater for the incoming solution interposed in said blow off conduit, and a valved liquid pressure supply pipe communicating with said preheater, for flushing it independently of the supplying of liquid under pressure to said boiler.

In testimony whereof I have signed my name to this specification.

GUSTAV ULLMANN.
